UNITED STATES PATENT OFFICE.

FREDERICK C. STIMMEL, OF CHATTANOOGA, TENNESSEE, ASSIGNOR TO THE CASEY-HEDGES CO., A CORPORATION OF OHIO.

HAND STOKER.

Application filed April 5, 1922. Serial No. 549,913.

To all whom it may concern:

Be it known that I, FREDERICK C. STIMMEL, a citizen of the United States, residing at Chattanooga, in the county of Hamilton and State of Tennessee, have invented certain new and useful Improvements in Hand Stokers, of which the following is a full, clear, and exact specification.

This invention relates to hand stokers for boiler furnaces, and has for its object to provide an improved progressive feed grate which may be operated by hand.

A special object of the invention is to provide a grate of the character described in which the rocking or oscillating grate members are normally arranged as a series of horizontal steps which will prevent the fuel from tobogganing down the grate. Inclined stationary grate members are arranged between adjacent rocking members and serve as tie bars between the bearing bars or side rails which support the grate. Said stationary grate members carry the journal bearings for the rocking members so that the entire grate surface is supported well above the side rails or bearing bars which are consequently not exposed to the action of the fire that might cause sagging thereof and render the grate inoperative.

The invention will be first hereinafter described in connection with the accompanying drawings, which constitute part of this specification, and then more specifically defined in the claims at the end of the description.

In the accompanying drawings:

Figure 1 is a longitudinal vertical section through a boiler furnace, showing a hand stoker constructed substantially in accordance with this invention mounted therein in elevation.

Figure 2 is a similar view showing the grate or stoker in section and the rocking members thereof in raised position, as when the fuel is being fed forward or downward into the furnace.

Figure 3 is a similar view showing the rocking grate members in lowered position and the dump plate dropped.

Figure 4 is a broken plan view of the lower end portion of the grate or stoker, the front dead grate bar at the upper end of said grate being also shown in plan.

Figure 5 is a detailed longitudinal sec-

tion of the lower end portion of the grate or stoker with parts broken away and removed.

Figure 6 is a detailed end view of the connection between the longitudinal bearing bars and caps at the lower end of the grate and the transverse tie bar at that point.

Figure 7 is a detailed view of one end of the front dead grate bar at the upper end of the grate or stoker, and

Figure 8 is a section on the line VIII—VIII of Figure 5.

As shown in Figure 1, the firebox of a boiler furnace is indicated at 1, the fuel door leading thereto being indicated at 2, the fire wall at 3 and the boiler at 4. An arch 5 is preferably constructed over the front end of the firebox to force the volatile gases over the hot bed of coals at the rear end of said firebox, thus preventing smoke which would otherwise be caused by the incomplete combustion of said volatile gases that are first distilled off in the process of burning coal.

The inclined stoking or progressive feed grate 6 is mounted in the firebox 1 and extends from the fuel door 2 to the fire wall 3. Said grate comprises a plurality of normally horizontal rocking members 7 and a plurality of stationary inclined grate members 8 alternating with said rocking members, whereby the fuel may be readily fed forward into the furnace step by step when the rocking members are raised, but the tobogganing of said fuel is prevented.

The grate members are supported by longitudinal bearing bars or side rails 9 arranged in inclined position at the sides of the grate, the front upper ends of said bars being mounted on stands 10 below the fuel door, while the rear lower ends of said bars are secured to a transverse tie bar 11 imbedded in the fire wall 3. Said bars 9 have a series of long lugs 12 alternating with short lugs 13 on their upper inclined edges. The stationary grate members 8 are bolted at 80 to the long lugs 12 and thus serve as tie bars for said longitudinal bearing bars 9. The short lugs 13 serve to support the free upper edge portions of the rocking grate members 7 when they are in normal lowered position. At the ends of the stationary grate bars there are bearing

notches 14 for the trunnions or pivot pins 15 on the rear edges of the rocking grate members. The stationary grate members are slotted at 16 and the rocking members 5 at 17 to allow ashes to pass through them.

The rocking grate members 7 have depending arms 18 joined thereto in line with the trunnions 15 and pivoted at their lower ends to link bars 19 extending along the inner faces of the bearing bars 9 and connected near their upper ends by links 20 to a hand lever 22 mounted in a foot plate 21 outside the furnace. Said lever 22 is adapted to be oscillated in said foot plate 10 for rocking the members 7 of the grate from the position shown in Figures 1 and 3 to the position shown in Figure 2, and vice versa, for progressively feeding the fuel introduced through the door 2 onto the upper end of the grate forwardly step by step 15 along the downwardly inclined grate members.

Just inside the fuel door a front dead grate bar 23 extends to the first rocking grate member. Said bar 23 is bolted as at 24 to upstanding lugs 25 on the front ends of the bearing bars 9 and is substantially T-shaped in cross section. The inner top flange 26 of said bar 23 is preferably perforated at 27, Figure 4, to permit ashes to pass through it.

The tie bar 11, which is seated in the fire wall 3 and supports the lower ends of the bearing bars 9, also has bolted thereto cap rails 28, as best shown in Figures 5 and 6. Said cap rails rest upon the lower end portions of the bearing bars 9 and have notches 29 in which are journaled trunnions 30 on the rear edge of a dump plate 31 which normally is arranged in a horizontal position, as illustrated in Figures 1, 2 and 4, and extends between said cap rails at opposite sides of the grate and from the fire wall to the lowest stationary grate member 8. The front ends of said cap rails have depending lugs 32 bolted to the lowest ones of the long upstanding lugs 12 on the bearing bars or rails 9, as best shown in Figure 5. The dump plate 31 has depending arms 33 at its free edge to which are pivotally connected an actuating rod or bar 34 extending through the front plate of the furnace and having a notch 35 for retaining it in advanced position to support the dump plate 50 in horizontal position, Figures 1 and 2. As shown in Figure 3, when the rod 34 is raised at its outer end to disengage its notch 35 from the front plate 36 of the furnace, said rod may be pushed inward for dropping the dump plate to discharge accumulated ashes therefrom into the ash pit 37.

I claim:

1. In a stoker, the combination with a grate having alternating stationary and

rocking transverse grate bars, said stationary bars being inclined and the rocking bars being normally horizontal, of means for rocking said latter bars for progressively feeding fuel along the grate.

2. In a stoker, the combination with an inclined grate having alternating stationary and rocking transverse grate bars, said rocking bars being normally arranged as a series of horizontal steps, of means for rocking said latter bars for progressively feeding fuel down the incline of the grate.

3. In a stoker, the combination with an inclined grate having alternating stationary and rocking transverse grate bars, the latter bars being normally arranged as a series of horizontal steps, of means for rocking said latter bars for progressively feeding fuel down the incline of the grate, a dump plate 80 at the inner end of the grate, and means for actuating said dump plate.

4. In a stoker, a grate comprising, in combination alternating stationary and rocking transverse grate bars, and side rails 90 to which said stationary bars are fastened and on which the free edges of the rocking bars are supported in normal position, and trunnions on said rocking bars journaled in said stationary bars well above said side rails.

5. In a stoker, a grate comprising, in combination alternating stationary and rocking transverse grate bars, and side rails having spaced upstanding lugs, said stationary bars being fastened to said lugs and having journal notches spaced above the same, said rocking bars having trunnions to fit in said notches of the stationary bars, and the free edges of said rocking bars being supported on said rails when in normal position.

6. In a stoker, a grate comprising, in combination alternating stationary and rocking transverse grate bars, and side rails having spaced lugs along their upper edges, said stationary bars being fastened to said rails and having the rocking bars journaled therein, and the free edges of said rocking bars being supported on said lugs when in normal position.

7. In a stoker, a grate comprising, in combination alternating stationary and rocking transverse grate bars, and side rails having spaced lugs along their upper edges, said stationary bars being fastened to alternate ones of said lugs, and the free edges of the rocking bars being normally supported on the other ones of said lugs.

8. In a stoker, a grate comprising, in combination alternating stationary and rocking transverse grate bars, and side rails for supporting said stationary bars and arranged well below the grate surface, bearings on said stationary bars, trunnions on said rocking bars engaging said bearings, arms depending from said rocking bars, and means 125 for supporting said stationary bars and arranged well below the grate surface, bearings on said stationary bars, trunnions on said rocking bars engaging said bearings, arms depending from said rocking bars, and means 130

extending along the inner faces of said rails for actuating said arms in unison.

9. In a stoker, a progressive feed grate having alternating stationary and rocking transverse grate bars, the latter bars being normally arranged as a series of horizontal steps, the stationary bars being inclined, and both kinds of bars being slotted for the purpose specified.
10. In a stoker, a progressive feed grate comprising, in combination, grate bars and side rails along which said bars are mounted, a dump plate arranged between the inner ends of the side rails, said rails extending to the inner end of said dump plate and caps covering the inner end portions of the rails and extending along the sides of said

dump plate, the latter being journaled in said caps.

11. In a stoker, a progressive feed grate comprising, in combination, grate bars and side rails along which said bars are mounted, a tie bar connecting the inner ends of said rails, a dump plate arranged between the inner ends of said rails, and caps covering the inner ends of said rails, each cap being fastened at one end to said tie bar and at the other end to one of the rails, said caps extending along the sides of said dump plate, and the latter being journaled in said caps.

In testimony whereof I have signed my name to this specification.

FREDERICK C. STIMMEL.
